UNITED STATES PATENT OFFICE.

MELVIN G. FULLER, OF WORCESTER, MASSACHUSETTS, ASSIGNOR TO
ARCHELAUS M. HOWE, OF SAME PLACE.

DIE.

SPECIFICATION forming part of Letters Patent No. 508,694, dated November 14, 1893.

Application filed June 13, 1893. Serial No. 477,424. (No model.)

To all whom it may concern:

Be it known that I, MELVIN G. FULLER, residing in Worcester, in the county of Worcester and State of Massachusetts, have invented 5 an Improvement in Dies, of which the following description, in connection with the accompanying drawings, is a specification, like letters on the drawings representing like parts.

My invention relates to improvements in 10 dies for cutting blanks of various shapes out of leather, rubber, pasteboard or similar materials.

The object of my invention is to provide a 15 cutting die which will leave the blanks, when cut, with a beveled edge, that is, with the upper surface of each blank less in area than its under surface.

My invention consists in a cutting die, the 20 inner wall of which near the cutting edge is beveled or inclined inwardly and is inclined outwardly above the plane in which the inwardly inclined bevel terminates, sufficiently 25 to afford a clearance space through which the blank may pass through and out of the die as easily and freely as out of an ordinary open die.

My invention also consists in a cutting die, 30 the outer wall of which, near the cutting edge, is substantially at a right angle to the plane in which the cutting edge is situated, and the inner wall of which near the cutting edge is beveled or inclined inwardly, and is inclined outwardly above the plane in which the inwardly inclined bevel terminates sufficiently 35 to afford a clearance space for the purpose above described.

In ordinary cutting dies, the inner wall near 40 the cutting edge is substantially at a right angle to the plane in which the cutting edge is situated, and the outer wall, near the cutting edge, is inclined outwardly. The edge of a blank cut out by such a die by reason of 45 the beveled outer wall, is usually slightly less in area on its lower surface than on its upper surface.

Referring to the drawings, Figure 1, is a 50 side elevation of a handle die for cutting heel lifts, embodying my invention. Fig. 2, is a vertical section on line 2,2 of Fig. 3, the han-

dle being represented as broken off. Fig. 3, 50 is a transverse section on line 3, 3 of Fig. 1.

A is the blade of the die, and B the handle.

c, c is the cutting edge of the blade and d the top, or as it is often called, the back of the blade. The outer wall of the die near the cutting edge upward for a distance e, e, greater than the thickness of the material to be cut, is substantially vertical, that is, it stands at a right angle to the plane in which the cutting edge c, c lies. The inner wall, from the cutting edge upward, for about the same distance, c, f, is beveled, or inclined inwardly. The inner wall above the plane in which the bevel c, f, terminates, is inclined outwardly to the top or back of the die, and, in order to insure the strength of the blade with as little metal as possible, the outer wall from e to d is made about concentric with the inner wall from f to d; but the shape and dimensions of the outer wall from e to d are immaterial, so long as the strength of the die is not impaired thereby. The area inclosed by the inner wall, at the top or back of the die should be equal to and preferably greater than the area at the cutting edge, to permit the free passage of 75 the blanks.

I have shown the outer wall near the cutting edge as substantially at a right angle to the plane in which the cutting edge lies, as, with this construction, the desired bevel on 80 the edge of the blank can be more easily and certainly secured, but the bevel or inclination of the outer wall near the cutting edge may be as in ordinary dies, provided that the inner wall is constructed as above described. 85

In operation, as the cutting edge is forced into the leather or other similar material to be cut, the blank, as it is being cut, is curved from its edges upwardly and inwardly toward the center of the blank, by reason of 90 the bevel c, f. When the next and following blanks are cut, the first blank will be forced up above the level c, f into the enlarged, or "clearance" space f, d, whence it may be readily removed by inverting the die, or if 95 the die is cut full of blanks, the first blank will be raised above the level of the back d, and may be slipped out horizontally beneath

the handle B. Each blank will be found to be cut beveling and will have a beveled, or, as it is sometimes termed a "standing" edge, a result which is desirable, especially in soles 5 and heel lifts for boots and shoes.

The distance to which the bevel c, f, shall extend is determined by the thickness and character of the material to be cut. In the case of sole leather, I have found it desirable 10 to make it about equal to the average thickness of the leather.

I am aware that cutting dies have been heretofore made to cut blanks and leave them with beveled or standing edges, but in all 15 such dies known to me, no provision has been made for clearance above the plane in which the bevel (corresponding to c, f) terminates, and consequently when a blank was cut, it was necessary to force it out from the die in 20 the reverse direction from which it entered. This, if done by hand, was, of necessity, slow, and, if done by a follower, as shown in United States Patent No. 110,762, of January 3, 1871, required more force to operate the die than 25 is required with my improved die, in order to overcome the resistance of the springs which actuated the follower. Moreover the use of a follower tends to prevent cutting a beveled edge on the blank, which is the object to be 30 attained, because the follower does not permit the blank to be curved upwardly and inwardly toward its center, under the action of the beveled inner wall near the cutting edge.

I have shown my invention as embodied in 35 a heel die, and, as in heel lifts, it is desirable to have the edge of the lift vertical which forms a part of the breast of the heel, I have left the inner wall of the die from g to h, Fig. 3, vertical, and the outer wall inclined out-

wardly, as at c', k, Fig. 1, in order to cut the 40 breast of the lift as it would be cut by an ordinary die. Around the curved portion of the blade, the inwardly inclined bevel c, f, is employed; but I consider as of my invention 45 a die in which the entire cutting edge or any substantial part thereof is formed as above and for the purpose described and provided with a clearance space above.

When it is desired that the blank should have a beveled edge around its entire periphery, as in a sole die, the inwardly inclined bevel c, f would be used exclusively. 50

It is obvious that my improved die may be provided with a handle as shown in the drawings or may be actuated by a machine applied to the back of the blade. 55

What I claim as my invention is—

1. A cutting die the inner wall of which, near its cutting edge is beveled inwardly, and is inclined outwardly above the plane in which 60 the inwardly inclined bevel terminates, substantially as and for the purpose set forth.

2. A cutting die the outer wall of which, near its cutting edge, is substantially at a right angle to the plane in which its cutting 65 edge is situated, and the inner wall of which near the cutting edge is beveled inwardly, and is inclined outwardly above the plane in which the inwardly inclined bevel terminates, substantially as and for the purpose set forth. 70

In testimony whereof I have signed my name to this specification in the presence of two subscribing witnesses.

MELVIN G. FULLER.
